CHILD'S SLED

Zygmunt Kubiak, Cleveland, Ohio

Application May 26, 1949, Serial No. 2,900

Term of patent 14 years

(Cl. D34—15)

To all whom it may concern:

Be it known that I, Zygmunt Kubiak, a citizen of the United States, residing at Cleveland, county of Cuyahoga, and State of Ohio, have invented a new, original, and ornamental Design for Child's Sled, of which the following is a specification, reference being had to the accompanying drawing, forming a part hereof:

Fig. 1 is a perspective view of a child's sled, showing my new design;

Fig. 2 is an elevation of the sled as it appears from the rear thereof; and

Fig. 3 is a fragmentary cross-sectional view taken on line 3—3 of Fig. 1, showing the appearance of the runners of the sled.

I claim:

The ornamental design for a child's sled, substantially as shown.

ZYGMUNT KUBIAK.
